UNITED STATES PATENT OFFICE.

JOSEPH I. RICHARDS, OF SAN FRANCISCO, CALIFORNIA.

ARTIFICIAL-TOOTH ATTACHMENT AND METHOD OF MAKING AND UTILIZING THE SAME.

1,296,009.

Specification of Letters Patent.

Patented Mar. 4, 1919.

Application filed October 29, 1918. Serial No. 260,103.

To all whom it may concern:

Be it known that I, JOSEPH I. RICHARDS, a citizen of the United States, residing at the city and county of San Francisco and State of California, have invented certain new and useful Improvements in Artificial-Teeth Attachments and Methods of Making and Utilizing the Same, of which the following is a specification.

10 My invention relates to artificial teeth, particularly those known as plate-tooth-facings, their manufacture and their utilization in all classes of crown and bridge work.

15 The object of my invention is to provide a simple, durable, inexpensive and practical attachment for artificial-tooth-facings, and uniting them to bridge-work, Richmond crowns, standard crowns, porcelain crowns and all classes of such teeth commonly used 20 and known as crown or bridge-work.

25 In attaining these objects, I eliminate entirely the use of platinum and I also reduce the quantity of gold necessary to secure results which are both practical and more economical than heretofore.

30 To these ends my invention consists in the novel attachments, and in the method of making and utilizing the same, as I shall now fully describe by reference to the accompanying drawings, in which—

Figure 1 is a posterior elevation of an artificial-tooth-facing.

Fig. 2 is a cross section of the same on the line 2—2 of Fig. 1, showing the gold-foil lining 3 in the socket or opening 2 of the facing.

Fig. 3 is a cross-section of the facing showing the fitting to the gold lined socket of the metallic gauze shell or clip 4 and the temporary binder of flux wax 6.

Fig. 4 is a cross section of the facing, as in Fig. 3, showing the addition of the gold foil backing 7 to the lingual surface, the imposition on said backing of the metallic gauze backing sheet 8, and the turning over 45 of the projecting or rim portion 5 of the gauze shell or clip 4 to hold the two backings.

Fig. 5 is a section, enlarged, of the tooth-facing, as in Fig. 4, showing the gold solder 9 and the effect of flowing it over the posterior tooth surface.

50 1 is an artificial-tooth-facing of baked porcelain with the socket or opening 2 on the lingual surface. There may be one or

more of these openings of any approved shape, such, for example, as the dove-tail form shown. The opening 2 is lined, as shown in Fig. 2, with pure or fine gold 3, say, for example, 24 K. gold foil, known as 60 #30 or #60, and which is commonly used as a filling material. The gold lining 3 can be pressed into position or fluxed to the porcelain during the process of manufacture.

65 Into the gold lined opening 2, as seen in Fig. 3, is pressed a shell or clip 4 of metallic gauze. The gauze may be gold, but in practice, a baser metal will serve as well, and be more economical. This shell or clip is so 70 pressed into the gold lined dove-tail opening as to adapt itself closely and intimately thereto throughout all its wall surface, and a portion or rim of said shell indicated by 5, is left projecting from the surface of the 75 facing to serve as a binding ring in the progressive assembling of parts and construction.

The opening 2 thus lined by the gold 3 and the gauze 4 is now partially filled with 80 a flux wax 6, as a temporary binder.

The artificial-tooth-facing and its attached parts, as thus far described is the condition of the article as it leaves the manufacturer and is placed on sale for use 85 by practitioners.

In the hands of the dentist, the entire lingual surface of the tooth-facing is covered with pure gold foil 7, as shown in Fig. 4, and over this is placed a sheet of metallic 90 gauze 8. The binding ring 5 of the metallic gauze shell or clip 4 is bent down upon the gauze backing sheet 8, to act as a binder.

95 The completed facing 1, together with other facings similarly constructed and prepared, are now assembled and all are united with gold solder 9 usually employed in such work. The gold solder covers the whole back of each facing and bridges and unites each facing of the assemblage. The effect 100 and position of the gold solder 9 is shown in Fig. 5. It flows through the interstices of the gauze backing sheet 8 and unites homogeneously with the gold foil backing 7. The heat evaporating the temporary flux wax 6, 105 allows the gold solder to flow into the opening 2 of the facing, and through the interstices of the gauze shell or clip 4, and to unite homogeneously with the gold lining 3. There is thus formed a practically solid 110

gold key holding the facing and uniting all the facings in the assemblage. When baser metals are used for the gauze members, for the sake of economy, they are so completely covered by and incased in the gold that they are not exposed to the mouth secretions and will serve their proper function as well as if made of gold, though, manifestly gold gauze could be used if desired.

10 By the use of the gauze, I secure not only its function as a binding mesh for the gold solder, but also its protective function against the heat, which being sufficient to melt and flow the 18 K. gold solder to its 15 union with the gold foil members would, without the intervention of the gauze melt and burn said foil. But with the gauze screen present the gold solder unites with the gold foil forming a solid mass and covering the inner surface of the whole assemblage entirely with gold.

The economic features of my invention are now apparent. The use of platinum which is now prohibitive both on account of 25 price and the imperative necessity for its use in other arts, is done away with. Platinum pins for artificial tooth-facings have heretofore been required as they alone will stand the heat of baking in the manufacture. 30 But by my construction and method a substitute is found in the gold key as I have described.

The gold and the porcelain tooth are in perfect contact and will allow no fluxes to 35 enter which would tend to crack the porcelain tooth. In the finished work each tooth is held securely to the bridge by the gold filled key.

I claim:

40 1. As a new article of manufacture an artificial-tooth-facing comprising a porcelain member having in its lingual surface a socket; a gold foil lining in said socket; a metallic gauze shell fitted closely to said 45 gold-foil lining; and a body of flux wax to temporarily hold said lining and shell in place.

50 2. As a new article of manufacture an artificial-tooth-facing comprising a porcelain member having in its lingual surface a socket; a gold foil lining in said socket; a metallic gauze shell fitted closely to said gold-foil lining, said gauze-shell having a

portion projecting from the inner surface of the porcelain member; and a body of flux 55 wax to temporarily hold said lining and shell in place.

3. Crown or bridge work comprising an artificial-tooth-facing having in its lingual surface a socket; a gold foil lining in said 60 socket; a metallic-gauze-shell fitted closely to said gold-foil lining; a gold foil backing for the lingual surface of the facing; a metallic gauze backing sheet over said gold foil 65 backing; and a body of gold solder covering the gauze backing, permeating its interstices and united with the gold foil backing, and permeating the gauze shell in the socket and united with the gold foil lining in said 70 socket.

4. Crown or bridge work comprising an artificial-tooth-facing having in its lingual surface a socket; a gold foil lining in said 75 socket; a metallic-gauze-shell fitted closely to said gold-foil-lining, said shell having a portion projecting from the inner surface of the facing and adapted to be bent down thereupon; a gold-foil backing for the lingual surface of the facing; a metallic-gauze backing sheet over said gold-foil back- 80 ing, both backings being held by the bent down portion of the gauze-shell; and a body of gold solder covering the gauze backing, permeating its interstices and united with the gold foil backing, and permeating the gauze 85 shell in the socket and united with the gold foil lining in said socket.

5. The method of manufacturing an artificial-tooth-facing ready for the use of dental practitioners which consists in first making a porcelain facing with a lingual surface socket; then pressing into said socket a gold-foil lining; then pressing into said 90 socket upon the gold-foil lining a shell of metallic gauze, leaving a portion of said 95 shell projecting from the socket; and finally placing a body of flux wax in the socket to hold the lining and shell in place.

In testimony whereof I have signed my name to this specification in the presence of 100 two subscribing witnesses.

JOSEPH I. RICHARDS.
